THEODORE J. SCOFIELD, OF JACKSON, MICHIGAN, ASSIGNOR TO THE SPARKS-WITHINGTON COMPANY, OF JACKSON, MICHIGAN, A CORPORATION OF OHIO

SIGNALING DEVICE

Application filed August 24, 1926. Serial No. 131,212.

This invention relates to certain improvements in signaling devices, and more particularly to signaling devices of the diaphragm type that are commonly used upon automobiles, motor boats, and other vehicles.

The main object of the invention is the production of a new and novel type of signaling device combining magnetic and rotary electric motor operation.

10 Other objects and advantages relate to the details of the structure and the method of adjusting and correlating the parts thereof, all as will more fully appear from the following description taken in connection with 15 the accompanying drawings, in which:

Figure 1 is a longitudinal sectional view of a signaling device of this invention.

Figure 2 is a section on line 2—2, Figure 1.

20 Figure 3 is a section on line 3—3, Figure 1. Figure 4 is a longitudinal section through a modified form of signaling device of this invention.

25 Figure 5 is a longitudinal sectional view illustrating the bearings for the armature shaft and the method of adjusting the same.

Figure 6 is a sectional view through a modified form of adjustable bearing.

Figure 7 is a section taken on line 7—7, 30 Figure 4.

Figure 8 and 9 are diagrammatic views of usable circuits.

The signaling device shown in Figures 1 to 3 comprises a projector —1—, a front case section —2— and a rear case section —3—, 35 between which sections the marginal portion of a substantially circular metallic diaphragm —4— is clamped in any suitable manner, as by means of bolts —5—.

The rear case section —3— is formed with 40 a central opening —84— in this instance substantially concentric with a cylinder —6— of magnetic material, such as any suitable metal having a radially and outwardly extending flange —7— at its forward end and brackets —8— extending from the flange —7— and secured to the case section —3— in any suitable manner as by rivets or otherwise.

45 The magnetic coil —9— is wound about the cylinder —6— and within the angle formed 50 between the cylinder —6— and the flange

—7— and is connected in circuit for the passage of current in any suitable manner, such as one of those hereinafter described.

The diaphragm —4— carries an armature or core —10— positioned within and concentric with the cylinder —6— and for the purpose of adjusting the armature —10—, it is provided with a reduced screw threaded portion —11— threaded through a collar —12— secured to the diaphragm at substantially its central portion in any suitable and well known manner, such as that illustrated. The armature —10— is locked in any desired position of adjustment with respect to rotor —13— by means of nut —14— threaded upon the projecting portion —11—.

In this particular illustration, the rotor —13— is mounted upon and rotates upon an axis at substantially right angles to the axis of the armature —10— and is positioned at the rear of the case section —3— opposite the central opening —84— in the case section —3—, which opening is preferably substantially concentric with the armature —10—.

70 The cylinder —6— in addition to forming a support for the coil —9— also relieves the tendency for the armature —10— to pull off center in case the armature is not absolutely in the center of the coil —9— the armature 75 10 being positioned concentrically of the cylinder 6. The rotor —13— is in the form of a spider of a plurality of radiating arms —14— separated by radial recesses or cut-out portions 15, and as the rotor is formed of magnetizable material, the arms —14— constitute 80 portions exerting comparatively great magnetic stress while the recessed portions —15— between the arms —14— constitute portions of little, if any magnetic stress, and it is by 85 reason of this fact that the structure operates in the manner that will hereinafter appear.

The rotor —13— is mounted upon the upper end of the armature shaft —16— of an ordinary electric motor —17— and the rotor —13— is mounted in such a manner upon the armature shaft —16— as to be freely rotatable with respect to the shaft, but is driven thereby through the medium of a flanged collar —18— pressed upon the armature shaft 90 100

—16— at a point adjacent the rotor —13— and provided with a pair of spaced upwardly projecting pins —19— and —20— which rotate with the collar and the armature shaft —16—. The rotor —13— is provided with a depending pin —21— which may be secured in a recess in the rotor.

Coil spring —22— has one end connected to the flanged collar —18— and its opposite end connected to the pin —21— so as to normally maintain pin —21— in contact with pin —20—, in which position with the motor rotating in the direction indicated in Figure 3, the armature and its shaft are free to rotate with respect to the rotor —13— until pin —19— comes in contact with pin —21—. In other words, the spring —22— holds the rotor —13— normally ahead of rotation of the armature shaft —16—, thereby allowing the armature to always start when current is applied to the motor for the reason that it allows the armature to start its rotation before it has to pick up its maximum load. This is particularly advantageous in case the armature stopped in low torque position, and this frequently happens.

The motor may be of any usual and well known construction and in this instance comprises a U-shape sheet metal case —23— having the forward end of its legs reduced, threaded and projected through a bracket —24— secured to the case section —3— in any suitable manner, and the ends of the U-shape case where they project through the bracket —24— are adapted to receive nuts —25— for rigidly securing the U-shape case to the bracket.

The upper end of the motor shaft has a bearing in the bracket —24— and the lower end of the motor shaft is provided with an adjustable end thrust bearing in the base of the U-shape case, as for instance by the use of a cup-shape screw —26— and locking nut —27—.

When the motor —17— and the coil —9— are simultaneously energized, the coil —9— magnetizes the armature —10—. As the arms or solid portions of the rotor —13— move past the armature —10— during rotation of the rotor, the magnetized armature —10— tends to draw the solid portions —14— of the rotor toward itself but as the rotor cannot move in that direction, the armature itself moves toward the arms or solid portions —14— of the rotor pulling the diaphragm —4— along with it. As one of the recesses —15— comes opposite the armature —10— there is little, if any, magnetic attraction between the armature —10— and the rotor and as a result the natural spring or resiliency of the diaphragm overcomes any existing magnetic attraction and the diaphragm swings away from the rotor —13—. The next arm or solid portion —14— again provides sufficient magnetic attraction between the armature

and the rotor so that the armature again moves toward the rotor and at the next recess —15— the diaphragm again swings away and in this manner vibration of the diaphragm to produce sound is effected.

The diaphragm —4— has a natural period of vibration of its own and in order to produce maximum sound must swing or vibrate at substantially this frequency, and to a considerable extent the natural frequency of the diaphragm governs the speed of the motor —17— as the motor will adjust itself to a speed at which it can perform the required function with the least exertion and the motor will substantially synchronize its speed of rotation to conform with the natural frequency of the diaphragm.

In Figures 4, 5 and 6, and 7 the rotary motor is arranged with the axis of its armature shaft substantially perpendicular to the diaphragm and substantially parallel with the axis of the armature —10—. In this case the armature —10— can be rigidly secured to the diaphragm as the necessary relative adjustment between the armature and the rotor —13— can be effected by mere endwise adjustment of the armature shaft. In this particular illustration, the rotor —13— is of slightly different form but involves in like manner as the rotor of Figures 1, 2 and 3, a series of radially projecting arms —14— separated by cut-out portions or radially recessed portions which produce little, if any, magnetic stress in connection with armature —10—.

The bearings for the armature shaft illustrated more clearly in Figure 5 constitute in themselves a novel structure applicable to any form of signaling device or motor in which adjustment of the armature shaft is desirable, while operation may be carried on with a minimum of friction.

In this structure the armature shaft —16— has its forward bearing in a flanged sleeve —30— threaded into the rear case —3— and provided with a lock nut —31— for maintaining the sleeve in desired position.

In Figure 5 the flange —32— upon the rear end of the sleeve —30— is formed with a ball race adapted to receive anti-friction balls —33— and the shaft —16— is formed with a cone —34— adapted to bear against the balls —33—. In this illustration, the cone —34— is secured to the shaft —16— and may, as shown, rest against the shoulder —35— formed on the shaft. The cone —34— is held in contact with the balls —33— by means of a spring —36— secured to the base of the U-shaped case —23— and extending across the rear end of the shaft —16— where it projects outwardly from its bearing in the case —23—.

The rear end of shaft —16— is preferably rounded, as shown, for substantially point contact with the spring bar —36—. With

this construction, it is possible to place considerable pressure upon the rear end of the shaft —16— holding the cone —34— firmly against the balls —33— without retarding 5 rotation of the armature. In Figure 6 a slightly modified form of adjustable bearing is illustrated in that a thrust washer —38— is substituted for the balls —33— and bears against the rear end of the flange —32— 10 and is held against the flange by means of a shoulder or disk —39— mounted on and secured to the shaft —16— at the rear of the thrust washer —38— and resting in like manner as cone —34— against shoulder 15 —35— upon the shaft —16—.

The operation of this structure in producing diaphragm vibration is the same as the operation described in connection with Figures 1 to 3. As before stated, the coil —9— 20 and motor —17— are simultaneously energized and in Figures 8 and 9 I have illustrated the coil and motor as connected in series and parallel respectively with a source of potential as battery —40—.

25 Altho I have shown and described specific structures as illustrative of embodiments of the invention, I do not desire to restrict myself to the details of form, construction or arrangement of the apparatus or the parts 30 thereof, as various changes and modifications may be made in each and all of the same without departing from the invention as set forth in the appended claims.

I claim:

35 1. A signaling device comprising a diaphragm, a rear diaphragm case including an apertured rear wall, a magnetic tube carried by said case upon the side of the rear wall facing the diaphragm and aligned with the 40 wall aperture, an electro magnet mounted on said tube, a movable core secured to the diaphragm and positioned substantially concentrically within said tube, a rotor positioned externally of the rear diaphragm case wall 45 and consisting of a plurality of arms separated by recesses and aligned with the removable core through the wall aperture, and means including an electric motor for rotating said rotor to bring the arms and recesses alternately opposite the core.

50 2. A signaling device including a diaphragm, a rear diaphragm case including an apertured rear wall, a tubular electro-magnet carried by said case upon the side of the rear 55 wall facing the diaphragm and alined with the wall aperture, a movable core secured to the diaphragm and positioned substantially concentrically within the tubular electro- 60 magnet, a member movable past the core and having radial arms spaced by intervening recesses exercising comparatively high and low magnetic stresses respectively upon the movable core, and an electric motor for operating 65 the last named member.

3. A signaling device including a diaphragm, a rear diaphragm case including an apertured rear wall, a tubular electro-magnet carried by said case upon the side of the rear wall facing the diaphragm and alined with the wall aperture, a movable core secured to the diaphragm and positioned substantially concentrically within the tubular electro-magnet, a rotary member movable past the core and having radial arms spaced by intervening recesses exercising comparatively high and low magnetic stresses respectively upon the movable core, and an electric motor for operating the last named member.

In witness whereof I have hereunto set my hand this 31st day of July, 1926.

THEODORE J. SCOFIELD.
